ESME EUGENE ROSAIRE, OF HOUSTON, TEXAS, AND ARTHUR DAVID KERNS, OF BLOOMFIELD, NEW JERSEY, ASSIGNORS TO WESTERN ELECTRIC COMPANY, INCORPORATED, OF NEW YORK, N. Y., A CORPORATION OF NEW YORK

METHOD OF AND APPARATUS FOR MANUFACTURING ELECTROSTATIC CONDENSERS

Application filed June 5, 1926. Serial No. 113,858.

This invention relates to a method of and apparatus for manufacturing electrostatic condensers and has for its principal object the construction of electrostatic condensers to 5 definite measured capacities in a simple, inexpensive and expeditious manner.

In accordance with the object of the present invention strips of paper or other dielectric and metal foil are assembled into a plurality of units which are individually subjected to pressure and passed through a heated impregnating solution, preferably paraffin, from which they pass to a common point where an additional strip of paper or other 10 dielectric is interposed between the units which are caused to adhere thereto. The composite units are then passed through a heated impregnating solution, also preferably paraffin, subjected to pressure for causing the 15 intimate association of the respective elements and for expelling any entrapped air and then wound in coil form until a predetermined capacity has been attained as determined by a capacity measuring device associated therewith.

It is believed that this invention will be clearly understood from the following detailed description and the accompanying drawing, in which

Fig. 1 is a schematic illustration of an apparatus by means of which the several steps of this invention may be practiced;

Fig. 2 is a wiring diagram of the electrical circuit for indicating when a condenser being wound has reached a predetermined capacity;

Fig. 3 is a fragmentary elevational view of a winding arbor with a condenser wound thereon showing the means for electrically connecting the condenser plates to the associated circuit during the forming of the condenser, and

Fig. 4 is an end view thereof.

In order to make clear the steps of the method, the schematic illustration of an apparatus by means of which it may be practiced will be described. Referring to Fig. 1 of the drawing, the numerals 10, 11, 12 and 13 represent supply rolls of paper or other dielectric material, and 14 and 15 supply rolls of tin foil or other material forming

the plates of the condensers, the width of the foil being slightly less than that of the paper as shown in Fig. 3. At 17 and 18 are indicated pairs of heated rollers between which the sets of paper and foil strips 10, 11 and 14, and 13 and 15 respectively are drawn, immediately upon leaving their respective supply rolls, to remove any moisture which may be contained therein. The rollers 17 and 18 may be heated either electrically or as illustrated by steam supplied from a suitable source (not shown) through a pipe indicated at 19 and passing axially through each of the rollers. Receptacles containing fused dielectric material, which may be paraffin, are indicated at 20, 21 and 22, which may be heated by gas burners 23. A roller 24 is carried in each of the receptacles 20, 21 and 22 around which the strips of paper and foil pass on their way through the receptacles, the paper strips it will be apparent being impregnated with the fused paraffin. Pairs of suitable pressure rollers are indicated at 25, 26 and 27, between which the paper and foil strips pass upon emergence from the paraffin baths 20 to cause a suitable adherence between the strips passing therebetween. Associated with the receptacle 22 is another set of pressure rollers 28, between which the various strips pass after leaving the pressure rollers 25 and 26 and before their joint entrance into the receptacle 22. Upon leaving the pressure rollers 27 the several impregnated strips of paper and associated strips of tin foil are wound upon a winding arbor 30 which may be rotated in any suitable manner, for instance by a hand crank (not shown).

It will be apparent upon causing the arbor 30 to be rotated in the direction indicated by the arrow (Fig. 1) that the several strips of paper and tin foil will be simultaneously drawn from their respective supply rolls and wound into a coil upon the arbor in the following manner:

The paper strips 10 and 11 together with the strip of tin foil 14 form a unit or one set of strips, which is advanced from its respective source of supply with the foil 14 outside of the two paper strips 10 and 11, between the heated rollers 17, which serve to posi-

tively remove any moisture contained in the paper strips, and thence under the roller 24 supported in the bath 20 which serves to impregnate the paper strips with paraffin. 5 Upon emergence from the bath 20 the several strips are drawn between the pressure rollers 25 to cause a close adherence of the impregnated dielectric strips 10 and 11 with the tin foil strip 14 to form a three ply composite 10 strip indicated at 31. Simultaneously with the advance of the strips 10, 11 and 14 between the heated rollers 17 through the paraffin bath 20 and between the pressure rollers 25, the paper strip 13 together with 15 the strip of tin foil 15 which forms a second unit is advanced from its respective source of supply and treated in a manner similar to that described in connection with the strips 10, 11 and 14 by being drawn between the heated rollers 18, through the paraffin bath 21 and between the pressure rollers 26 to form a two ply composite strip indicated at 32. During the continued advance of the composite strips 31 and 32 toward the winding 20 arbor 30 after being formed by the pressure rollers 25 and 26, respectively, the paper strip 12 is simultaneously advanced and associated therewith between the foil strip 14 and paper strip 13 of the composite strips 31 and 32 25 respectively, the whole being drawn between the pressure rollers 28, through the bath 22 where the several paper strips are further treated with paraffin and between the pressure rollers 27 to cause a close adherence of 30 the composite strips 31 and 32 into a single composite strip 33.

Upon the condenser being wound to a predetermined capacity, as indicated by a capacity measuring device associated therewith 40 to be described in detail hereinafter, the operator may sever the composite strips 31 and 32 at the points indicated by the numerals 34, without, however, severing strip 12. The winding of the coil is thereafter continued 45 until the balance of the strips 31 and 32 associated with the arbor 30 have passed through the bath 22, between the rollers 27 and wound upon the arbor 30 with a sufficient length of the unsevered paper strip 12 wound thereon 50 to form a protective covering. The paper strip 12 is then severed at a point indicated by the numeral 35 and the completed condenser roll removed from the arbor 30, and thereafter the severed ends of the composite 55 strips 31 and 32 are brought into engagement with opposite surfaces of the paper strip 12 and caused to adhere thereto, the operation being facilitated by their previous treatment in the paraffin baths 20 and 21. The free end 60 of the paper strip 12 is then associated with the winding arbor 30 and the forming of the condenser roll continues, as hereinbefore described, until the predetermined capacity has been obtained, the paper strip 12 serving 65 to thread the composite strips 31 and 32

through the bath 22 and between the rollers 27 and to the winding arbor 30.

Referring to Figs. 3 and 4 which illustrate the means for electrically connecting the metallic condenser plates 14 and 15 to the circuit during the winding of the condenser, the circuit serving to indicate when the condenser has reached a predetermined capacity, 36 and 37 indicate condenser terminals consisting of thin metal strips, preferably of tinned copper ribbon, which are slipped into position as the composite strips 31 and 32 are being formed into the single composite strip 33, the terminals 36 and 37 each being in electrical contact with one of the plates 14 and 15. Fixed to the arbor 30 is a collar 38 composed of insulating material, for instance, vulcanized hard rubber. Attached to the periphery of the collar 38 at diametrically opposite points is a pair of 85 spring clips 39 which, as clearly shown in Fig. 4, are designed to firmly engage the terminals 36 and 37. Secured to an insulating collar 40 in spaced relation with each other are a pair of contact rings 41 which are engaged by a pair of stationary brushes 42. 90

The circuit combined with a vacuum detector tube (Fig. 2), which is associated with the condenser during the forming thereof, in practicing the method hereinbefore described and designed to indicate to the operator when the condenser has reached a predetermined capacity will now be described. The terminals 36 and 37 of the condenser (Figs. 3 and 4) during the winding thereof 100 are connected to the circuit through the brushes 42 bearing upon the contact rings 41 carried by the winding arbor 30, as hereinbefore described. Referring to Fig. 2, the numeral 45 indicates a suitable oscillatory

circuit which includes a suitable source of current of constant frequency at approximately eighteen hundred cycles. The circuit 105 45 is connected to a vacuum tube 46 which has a tuned plate circuit consisting of a 110 variable inductance 47 and a condenser 48 in parallel, which represents the condenser being wound, the brushes 42 hereinbefore mentioned being connected into the tuned plate circuit at points 49 and 50. When the condenser 48 reaches a predetermined capacity 115 it forms a resonant circuit for the fixed frequency of the pulsating current flowing in the plate circuit of the tube 46, at which time a large current will flow in the resonant circuit. The value of the capacity may be varied by varying the inductance 47. It will, therefore, be apparent that at any value of capacity of the condenser 48 during the winding thereof other than that at which the tuned 120 plate circuit is in resonance, the current through the condenser 48 and the variable inductance 47 is much smaller than the resonance value. A very small portion of the inductance 47, as indicated at 53, is connected 125

to the grid electrode of a vacuum detector tube 54 which has a large amplification factor and the current flow through its plate circuit is reduced nearly to zero by a negative grid bias. A sensitive relay 55 is included in the plate circuit of the tube 54. When the tuned plate circuit of the tube 46 is in resonance with the impressed frequency, a large potential is induced upon the grid of the tube 54 by the current flowing in the variable inductance 47 which causes a rectified or unidirectional current to flow in the plate circuit of the tube 54, thereby energizing the relay 55 and closing a circuit which includes a signal lamp 57 which, in operating, indicates to the operator winding the condenser that the capacity thereof has reached a predetermined value.

What is claimed is:

1. The method of forming electrostatic condensers, which consists in simultaneously advancing a plurality of separate units of strips of fibrous material and strips of metal through a fused dielectric material, subjecting the several strips comprising each unit to pressure upon both faces immediately upon emergence therefrom so as to form the several strips into composite strips, interposing a strip of fibrous material between the composite strips, subjecting the composite strips and the interposed strip to pressure, advancing the whole through a fused dielectric material and again subjecting the same to pressure to cause a close adherence of the composite strip and the interposed strip into a single composite strip and forming the latter into a roll.

2. The method of forming electrostatic condensers, which consists in simultaneously heating and advancing a plurality of separate units of strips of fibrous material and strips of metal through a fused dielectric material, causing a close adherence of the several strips comprising each unit into a composite strip, interposing a strip of fibrous material between the composite strips, advancing the whole through a fused dielectric material, applying pressure to both faces thereof to cause a close adherence of the composite strips and the interposed strip into a single composite strip and forming the latter into a roll.

3. The method of forming electrostatic condensers, which consists in simultaneously advancing a plurality of strips of fibrous material and a strip of metal with the latter positioned outside of the former through a fused dielectric material, causing a close adherence of the several strips into a composite strip immediately upon emergence therefrom, interposing a strip of fibrous material into adjacent relationship with the strip of metal, advancing a strip of fibrous material and a strip of metal through a fused dielectric material, causing a close adherence of

the latter strips into a composite strip immediately upon emergence therefrom, advancing the whole through a fused dielectric material, subjecting the whole to pressure upon both its faces to remove excess dielectric and form a single composite strip and forming the latter into a roll.

4. The method of manufacturing electrostatic condensers, which consists in assembling a plurality of strips of dielectric and metallic elements in predetermined relation, interposing a dielectric strip between the thus assembled strips, advancing the strips through a treating bath, forming the treated strips into a roll, and continuously testing the metallic elements for capacity during such assembly.

5. In combination with apparatus for forming electrostatic condensers, means for assembling a plurality of fibrous and metallic elements arranged in predetermined relation into a roll, and means associated with the metallic elements and responsive when a predetermined capacity has been attained therein for indicating when the condenser in process of being formed has reached a predetermined capacity.

6. The combination with apparatus for forming electrostatic condensers, means for assembling a plurality of fibrous and metallic elements arranged in predetermined relation into a roll of a circuit including metallic elements of the condenser being formed and an inductance, a source of pulsating current associated therewith, and means operable when a condition of resonance is obtained between the circuit and the current source for indicating when the condenser in process of being formed has reached a predetermined capacity.

7. The combination with apparatus for forming electrostatic condensers, means for assembling a plurality of fibrous and metallic elements arranged in predetermined relation into a roll of a circuit including the metallic elements of the condenser being formed and an inductance, a source of pulsating current associated therewith, and means under the control of the circuit when resonance is obtained between the circuit and the current source for indicating when the condenser in process of being formed has reached a predetermined capacity.

8. The combination with apparatus for forming electrostatic condensers, means for assembling a plurality of fibrous and metallic elements arranged in predetermined relation into a roll of a circuit including the metallic elements of the condenser being formed and an inductance, a source of pulsating current connected thereto, a vacuum detector tube connected to the circuit, and electro-magnetically operated means connected in the plate circuit thereof and designed to be operated when resonance is ob-

tained between the first mentioned circuit and the current source for indicating when the condenser in process of being formed has reached a predetermined capacity.

9. The combination with apparatus for forming electrostatic condensers, means for assembling a plurality of fibrous and metallic elements arranged in predetermined relation into a roll of a circuit including the metallic elements of the condenser being formed connected in parallel with a variable inductance, a source of pulsating current connected to the circuit, a vacuum detector tube having its grid connected to the inductance, electromagnetically operated means connected in the plate circuit thereof and designed to be operated when resonance is obtained between the circuit and the current source, and an electrically operated signaling device and circuit therefor designed to be closed by the operation of the relay when the condenser in process of being formed has reached a predetermined capacity.

10. The combination with apparatus for forming electrostatic condensers, means for assembling a plurality of fibrous and metallic elements arranged in predetermined relation into separate composite strips and advancing the same to a common point, a receptacle containing a fused dielectric material, a strip of fibrous material threaded therethrough, means for causing an adherence of the composite strips to the latter strip of fibrous material, means for advancing the associated strips through the material and compressing the same upon emergence therefrom into a single composite strip and forming the latter into a roll, of means associated with the metallic elements and responsive when a predetermined capacity has been attained therein for indicating when the condenser in process of being formed has reached a predetermined capacity.

11. The method of operating an apparatus for forming electrostatic condensers, wherein two outer strips and an inner strip are simultaneously passed through a series of rolls and wound upon an arbor, which consists in severing at a determined instant the outer strips at a point to the rear of said rolls, continuing the winding of the inner strip to complete the condenser, severing the inner strip at a point forward of the rolls, attaching the outer strips to the inner strip at a point to the rear of the rolls, and repeating the operation.

12. The method of forming electrostatic condensers by means of an apparatus comprising a series of rolls and an arbor, which comprises simultaneously passing two outer strips and an inner strip through the rolls to the arbor, severing the outer strip at a point to the rear of said rolls, continuing the winding of the inner strip to complete the condenser, severing the inner strip at a point

forward of said rolls, causing the ends of the outer strips to adhere to the inner strip at a point to the rear of said rolls, and repeating the operation.

13. In an apparatus for manufacturing electrostatic condensers, a rotating arbor for winding a plurality of dielectric and metallic elements in predetermined relation thereon, contacting means carried by the arbor for making an electrical connection to the rotating metallic elements, and means engaging the contacting means for continuously testing the elements for capacity.

In witness whereof, we hereunto subscribe our names this 7th day of May A. D., 1926.
